(57) **CLAIM**

The ornamental design for a carp marble fountain, as shown and described.

DESCRIPTION

FIG. 1 is a right perspective view of a carp marble fountain showing my new design;

FIG. 2 is a left perspective view thereof;

FIG. 3 is a rear view thereof; and,

FIG. 4 is an inverted view thereof.

The broken line showing is for illustrative purposes only and forms no part of the claimed design.
